UNITED STATES PATENT OFFICE.

THOMAS KLIPFEL, OF CHICAGO, ILLINOIS, ASSIGNOR TO UNION WIRE MATTRESS COMPANY, OF CHICAGO, ILLINOIS, A CORPORATION OF ILLINOIS.

SUPPORT FOR BED-BOTTOMS.

SPECIFICATION forming part of Letters Patent No. 716,055, dated December 16, 1902.

Application filed January 13, 1902. Serial No. 89,508. (No model.)

To all whom it may concern:

Be it known that I, THOMAS KLIPFEL, a citizen of the United States, residing at Chicago, in the county of Cook and State of Illinois, 5 have invented certain new and useful Improvements in Supports for Bed-Bottoms, of which the following is a specification.

My invention relates to supports for bed-bottoms, and more particularly to elastic or 10 flexible supports for the woven-wire bed-bottoms which are now in extensive use. These woven-wire bed-bottoms possess in themselves considerable longitudinal elasticity which comes into play when the bed is in use in sup- 15 porting the weight of the occupant or occupants thereof, and in order to prevent too great a central dip thereof it has hitherto been found desirable to provide some manner of underlying support therefor. These 20 supports have been of various kinds and have possessed varying degrees of efficiency; but the chief desideratum in a bed-bottom support of this character is to obtain a maximum amount of strength and resiliency or 25 elasticity with a minimum weight and number of coöperating parts.

The accomplishment of the above desideratum has been the principal object in view in my present invention, and in the embodiment 30 thereof hereinafter described I believe this result has been secured in a practical and economical manner.

In carrying out my invention I employ, in connection with the usual woven-wire or similar elastic bed-bottom, an underlying trans- 35 verse support for the intermediate or central portion thereof, this support comprising, essentially, a series of elastic cords or strands disposed longitudinally of the bed-bottom 40 frame, means for tensioning these strands by uniting laterally-adjacent strands through clip devices which may slide longitudinally thereof, and a series of coil-springs supported upon and engaging said clip devices. In as- 45 sociation with the foregoing elements I may also in accordance with my invention employ a series of transversely-disposed bars resting upon said strands and in themselves forming seats or supports for the lower ends of the coil- 50 springs, said bars directly overlying the clip

devices and preferably being bound thereto by the lower end or turn of the springs.

A bed-bottom support embodying my present invention in its preferred form is illustrated in the accompanying drawings, in 55 which—

Figure 1 is a bottom plan view of a bed-bottom frame, showing my invention in its simpler form applied thereto. Fig. 2 is a side elevation of Fig. 1 with one of the side bars 60 of the bed-bottom frame broken away and illustrating the manner of mounting and securing the springs in the underlying support and the overlying elastic covering constituting the bed-bottom proper. Fig. 3 is a de- 65 tail, partly in vertical section, illustrating the clip for uniting the strands of the support and further illustrating the manner of mounting and securing the base of the spring thereupon. Fig. 4 is a view similar to Fig. 1, but 70 illustrating the series of transverse supporting-bars employed in association with the elements shown in Fig. 1. Fig. 5 is a side elevation, partly broken away, of Fig. 4, this view being similar to the view shown in 75 Fig. 2. Fig. 6 is a detail, partly in elevation and partly in vertical section, transversely through one of the end members of the bed-bottom frame and showing the means of securing the supporting-strands at their 80 ends in and to said frame. Fig. 7 is an enlarged detail view of one of the coil-springs, illustrating its manner of connection to the overlying bed-bottom and its manner of support at its lower end. Fig. 8 is a similar enlarged detail 85 of the lower portion of Fig. 7, illustrating a slight modification in the means of uniting the spring at its lower end to the supporting-bar upon which it rests. Fig. 9 is an enlarged detail, in bottom plan view, showing the 90 supporting-bar, the lower end of the spring, the clip and the strands, and the manner of assembling and uniting said parts. Fig. 10 is a side elevational detail, partly in vertical section, showing the parts illustrated at the 95 lower end of Fig. 7 in a plane at right angles thereto; and Fig. 11 is a transverse vertical sectional view across the bed-bottom frame, showing a transverse row of springs in elevation and more particularly illustrating their 100

mode of connection to their underlying supports.

Referring to the drawings in detail, 11 designates the side members, and 12 the end members, of an ordinary rectangular bed-bottom frame. Secured in and to the top of the end members 12 in any suitable way is an ordinary woven-wire covering 13, (shown in Figs. 2, 5, 6, and 7,) constituting the bed-bottom proper. Also secured in said end members of the frame are a series of pairs of cords or strands disposed longitudinally of the bed-bottom frame and connecting the end members thereof below the bed-bottom 13. These 15 several pairs of strands I have designated by the reference-numeral 14, the individual strands of each pair being further distinguished as 14^a and 14^b. These strands are preferably simply coiled-wire cords which 20 unite in themselves the desirable features of strength and lightness, combined with a certain degree of longitudinal elasticity. The members of each pair are respectively united laterally by a series of clips, (designated by 15.) 25 These clips, as herein shown, consist each of a plain strip of sheet metal bent into the substantially oval form shown in Fig. 3, the adjacent ends of the strip being separated to provide an opening 15^a, whereby the clip may be passed 30 over a pair of adjacent strands, so as to embrace and hold the latter in close parallel relation, as indicated in Fig. 3, this construction of clip and mode of association with the strands enabling the clip to be readily ad- 35 justed longitudinally of the latter for the purpose of tensioning the strands, as well as to restrict or expand the area of the nest of springs constituting the direct intermediate elastic support for the bed-bottom. On either 40 side of the series of clips 15 I have shown a similar series of clips, (designated by 16,) which are similar in all respects to the clips 15, except that instead of being employed to connect the two strands of each pair they 45 are so applied as to connect the adjacent strands of adjoining pairs. Resting upon each one of the clips 15 and 16 thus disposed is an ordinary coil-spring 17, the lower end of which (designated by 17^a) is carried be- 50neath the upper surface of the clip and has its lower end bent upwardly and hooked through a vertical aperture in the clip, thereby locking the lower end of the spring against any tendency to unseat the same laterally 55 from its supporting-clip. The upper end of the spring is preferably secured in substantially fixed relation to the bed-bottom covering 13 by having the topmost turn of the coil threaded through the crimped and coiled fab- 60 ric of the covering, as shown in Fig. 7, after which the extreme end of the coil may be turned downwardly and inwardly to provide a hook against removal or displacement of the spring thus anchored. It will thus be ob- 65 served that the coil-springs 17 are secured at their upper ends in the bed-bottom fabric or covering and at their lower ends in the lon-

gitudinal and transverse members of the support, thus holding said springs securely against any movement except the vertical or up-and-down movement of the turns of the coil resulting from compression and release. By reason of the fact, however, that the clips 15 and 16 are slideable longitudinally of the supporting-strands the disposition of the coil-springs themselves relatively to the end rails of the frame may be varied by simply forcing the clips toward or from the end rails, this operation at the same time tending to vary the tension of the web-like support constituted by the strands united by the clips, as described.

In Figs. 4 and 5 and in the detail Figs. 7 to 11, inclusive, I have illustrated a slight modification of the principal construction already described, this modification residing, generally speaking, in the interposition of a series of transverse supporting-bars 18, laid above and across the longitudinal supporting-strands and forming seats for the coil-springs. These bars are preferably disposed between the lowermost complete turn of the coils and the upper surface of the tension-clips, as best shown in Figs. 7 and 8, each supporting-bar being engaged by all the springs in that transverse row of springs under which it lies. As shown in Fig. 7, the lower end of the wire constituting the coil of the spring is looped downwardly and around the supporting-bar and the clip, as indicated at 17^b, passing preferably across the clip between the two strands engaged by the latter and having its extreme end portion bent upwardly into the body of the coil, as shown at 17^c, thereby forming a complete band tying the spring, the supporting-bar, and the clip securely together against vertical separation, the strands themselves being likewise held against vertical separation from the overlying parts by reason of the inwardly-turned underlying ends of the clip, as best shown in Figs. 9 and 10. The construction last described I prefer to employ in connection with all of the springs except those lying nearest the side rails of the bed-frame and constituting the end springs of the several transverse rows or series. In the case of these latter instead of carrying the downwardly-looped end of the coil entirely around the supporting-bar and its underlying clip, as shown in Fig. 7, I aperture the clip and the supporting-bar and carry the upwardly-turned end therethrough, as indicated at 17^d in Figs. 8 and 11. The object of this latter construction, as will be readily understood, is to prevent longitudinal creeping of the supporting-bars, which would cause their ends to strike and rub against the side rails of the containing-frame in an objectionable manner. This latter construction not only prevents displacement of the supporting-bars relatively to the springs carried thereby in a direction longitudinally of the frame, but in a direction laterally thereof also.

In Fig. 6 I have illustrated in detail a simple and highly-efficient means which I have

devised for anchoring the upper and lower ends of the strands and of the woven-wire fabric constituting the bed-bottom in the end rails of the bed-bottom frame. As herein shown, the end rail 12 is made in two parallel bars or strips, the inner of which I have designated as 12^a and the outer as 12^b. The meeting faces of these strips are provided with an interfitting tongue-and-groove construction, the tongue being shown as formed on the inner edge or face of the strip 12^b at 12^d, and the groove being formed on the outer edge or face of the strip 12^a at 12^c. Between the tongue and groove thus formed the ends of the strands 14^a and 14^b, as well as of the covering fabric 13, are secured, being clamped therein by screws, (indicated at 12^e), uniting the two members 12^a and 12^b of the end rail. The end and side rails of the frame are conveniently and rigidly united by bolts 11^a, while as an additional means for securely uniting the parts 12^a and 12^b of the end rails the ends of the latter may be joined by sheet-metal or other straps or cleats, as shown at 12^f in Fig. 5.

25 The above-described construction permits the easy removal of both the covering fabric and its support from the frame by the simple loosening or withdrawal of the end strips 12^b, at the same time providing a secure and 30 effective anchoring device for securing said parts in place when in use.

35 My invention is not limited to the exact details of construction and relative arrangement of parts hereinabove described and shown, since it is obvious that the same might be considerably modified, if desired, to effect the same results in substantially the same way.

I claim—

40 1. In a bed-bottom support, the combination with the bed-bottom frame, of a series of longitudinal strands secured at their ends to the end rails of the frame, a series of clips connecting laterally-adjacent strands, and a 45 series of coil-springs superposed upon and at their lower ends embracing said clips and adapted to engage the fabric covering constituting the bed-bottom at their upper ends, substantially as described.

50 2. In a bed-bottom support, the combination with the bed-bottom frame, of a series of longitudinal strands secured at their ends to the end rails of the frame, a series of longitudinally-slidable clips connecting laterally-55 adjacent strands, and a series of coil-springs at their lower ends embracing said clips and adapted to engage the fabric covering constituting the bed-bottom at their upper ends, substantially as described.

60 3. In a bed-bottom support, the combina-

tion with the bed-bottom frame, of a series of longitudinal strands secured at their ends to the end rails of the frame, a series of clips connecting laterally-adjacent strands, a transverse supporting-bar overlying and resting 65 upon said clips, and a series of coil-springs seated upon said supporting-bar and embracing the latter and the underlying clips and at their upper ends engaging the fabric covering constituting the bed-bottom, substantially 70 as described.

4. In a bed-bottom support, the combination with the bed-bottom frame, of a series of pairs of longitudinal strands secured at their ends to the end rails of the frame, a transverse 75 row of clips connecting the pairs of each strand, a transverse row of clips connecting adjacent strands of adjoining pairs, a transverse supporting-bar overlying and resting upon each 80 row of clips, and coil-springs seated upon said supporting-bars and having their lower extremities looped around and embracing said bars and clips, substantially as described.

5. In a bed-bottom support, the combination with the bed-bottom frame, of a series of 85 longitudinal strands secured at their ends to the end rails of the frame, a plurality of transverse rows of clips connecting laterally-adjacent strands, a transverse supporting-bar overlying and resting upon each row of clips, 90 and a series of coil-springs seated upon said supporting-bars, certain of said springs having their lower extremities looped around and embracing said bars and clips, and one of said springs having its lower end passed beneath 95 and thence upwardly through apertures in its associate bar and clip, whereby said spring, bar and clip are all interlocked, substantially as described.

6. In a bed-bottom support, the combination with the bed-bottom frame, of a series of longitudinal strands secured at their ends to the end rails of the frame, a plurality of transverse rows of clips connecting laterally-adjacent strands, a transverse supporting-bar 105 overlying and resting upon each row of clips, and a series of coil-springs seated upon said supporting-bars, the intermediate springs having their lower extremities looped around and embracing said bars and clips, and the springs 110 at the ends of said bars having their lower ends passed beneath and thence upwardly through apertures in their respective bars and clips, whereby said springs, bars and clips are all interlocked, substantially as described. 115

THOMAS KLIPFEL.
